GOLF BALL MARKING DIE

Jesse D. Lyon, Cincinnati, Ohio

Application September 9, 1947, Serial No. 773,020

1 Claim. (Cl. 101—30)

1

The present invention relates to improvements in marking dies for golf ball marking machines and is particularly directed to a golf ball marking die, having novel type characters, which cooperates with the ball marking machine to produce clear cut and clean indicia in the ball surface that retain the original printing ink for longer periods of time than do ball markings now made.

An object of the invention is to provide a type face for a golf ball marking die having a single series of sharp, parallel ridges or projections which when inked and pressed into the cover of a golf ball produce therein a reverse mark characterized by narrow and relatively deep ink retaining grooves.

Another object of the invention is to provide a novel die construction wherein each character thereon has an ink carrying face consisting of a series of comparatively deep, closely spaced, parallel depressions and alternate elevations or ridges which are adapted to impress a spaced series of subsurface, ink retaining grooves and alternate ridges on a golf ball cover, said ridges having substantially wide and high body portions whereby the subsurface grooves are adapted to hold marking ink over long periods of time whilst the ball is submitted to hard treatment such as club impacts, cleaning compounds, and scrubbing actions.

A further object of the invention is to provide a die having character faces thereon which form in an impressionable golf ball cover a row of clearer and longer lasting impressions and which requires a less distorting pressure on the ball during the impression making operation.

Other objects will be apparent from the following specification and drawings which illustrate the preferred embodiment of my invention, it being understood that certain modifications may be made therein without departing from the spirit and scope of the invention set forth in the appended claim.

In the drawings wherein like reference numerals indicate similar parts:

Fig. 1 is a perspective view of my golf ball marking die.

Fig. 2 is an enlarged perspective view of a type used in the die illustrated in Fig. 1.

Fig. 3 is an enlarged plan view of a section of a golf ball cover showing the individual mark made by the die illustrated in Fig. 2.

Fig. 4 is an enlarged cross section taken on line 4—4 of Fig. 3.

Fig. 5 is an elevational view of a golf ball marked in accordance with my invention.

2

Fig. 6 is a side elevation of a golf ball marking machine depicting a manner in which the characters of my die are pressed into the surface of a golf ball cover.

5 In the drawings which illustrate a preferred embodiment of my invention the reference numeral 10 indicates an arcuate die which has a number of type characters 11 mounted in a row on its convex side 12. The die is used to make corresponding and complementary marks 111 intaglio in the exterior impressionable surface of a spheroid such as the cover of a golf ball 13 or the like. The die is brought into impression making contact with a golf ball by means of a golf ball marker 14 which is generally indicated in Fig. 6 and is fully set forth in my Patent No. 1,204,578.

20 Specifically the die 10 has a pair of opposed inwardly flared flanges 15 and 16 on its convex surface said flanges forming with the said surface an inverted T-slot 17 for mounting the parallelogram blanks 18 of individual types 19. One end 20 of the slot is opened so that the desired number and kind of type may be slid into the slot, 25 said row being held therein by forming a depression 21 in the flange adjacent the blank of the last type entered therein.

As most clearly illustrated in Fig. 2 wherein the letter "D" of the alphabet forms the character of the type, said type has a raised face 22 which lies in an offset plane parallel to the outside or exposed surface 23 of the parallelogram blank. Beard portions 24 taper upwardly from the blank to the type face 22 and intersect said type face in serrated edges 25, Fig. 2. Each 35 serrated edge is formed with an alternate series of sharp high points 26 and low points 27; opposed low points in the edges being joined by straight, non-intersecting grooves or depressions 28 deeply formed in the type face. As clearly 40 illustrated in Figs. 1 and 2 the grooves are closely spaced and are inclined with respect to the type row in the die and preferably are given an angle of inclination with respect to the longitudinal dimension of the type row approximating 45 45°. Adjacent grooves 28 form between them sharp ridges or elevations 29 which extend between opposed high points 26 formed in the serrated edges 25. In practice I mount a plurality 50 of smooth faced type upon a base plate and then form a series of grooves in said faces by traversing said faces with a milling tool having spaced, V-shaped teeth projecting therefrom. The teeth and the corresponding grooves formed in the type faces are preferably V-shaped for the reason that I have found it most economical and

55

expedient to provide a milling tool with pointed teeth which readily cut into the faces of the assembled types and form therein ridges having sharp and distinct marginal edges.

The remaining letters in the alphabet are constructed in a manner similar to the letter "D" illustrated in Fig. 2, said type including punctuation marks, numerals or other indicia so that an arrangement of the type may be made in the die to give an intelligent group of marks such as the name of an individual and if desired an abbreviation of the individual's street address and/or his city and state. As illustrated in Figs. 1 and 5 the individual's name set up in the die row and the impression made in a ball cover 13 is "J. Doe. 15 Cin. O."

The die characters are impressed in a golf ball cover by a mechanical pressure means such as the ball marker 14 wherein a pair of ball holding jaws 30 are mounted horizontally on a base 31 and are clamped about or released from a golf ball 13 by a lever 32. Extending upwardly from the base is a pivoted frame 33 which in turn has pivotally mounted thereon a die holder 34 capable of adjustment toward and away from the ball by a screw mechanism 35 operated through hand wheel 36. The die 10 is removably mounted in a slot formed in the arcuate portion 37 of the pivoted die holder. It will therefore be understood that inked impressions 38 corresponding in reverse to the type characters in the die are made in a golf ball cover by clamping the ball 13 in the jaws 30; inking the faces 22 of the types by means of an ink roller, or the like; inserting the inked die in the arcuate portion 37 of the die holder; thereafter turning hand wheel 36 until the desired pressure is exerted by the die characters against the ball and then rotating the frame 33 until the entire row of characters have been successively forced into the ball cover. The sharp ridges 29 in each type face make corresponding ink retaining grooves 39 in the bottom 40 of the type impression 38 in the ball cover.

I have found that these subsurface grooves formed in the bottom of type impressions in the ball cover hold ink therein over long periods of time so that the characters formed by my die are quite legible long after impression and even though the ball is subjected during this time to hard treatment such as club impacts, cleaning and scrubbing actions and contact with disfiguring or discoloring surfaces during flight. I ascribe these improved qualities of the type impression to the fact that the ridges in the type face upon impression making contact with the ball cover break down the resistance of the cover material thereby making a permanent distortion therein and that said ridges in the type face simultaneously carry ink into the distortion so formed.

Furthermore, I had found that golf ball covers

printed with dies having conventional smooth face type are subject to lateral deformation during impression making contact with said type due to the local spreading of the elastic ball cover in the area surrounding the type impression, and that the ink on the smooth face consequently is spread outwardly whereby blurred, unequally spaced marks or impressions were made in the ball cover. With my present golf ball marking die less pressure is needed to make a clear impression and the sharp ridges in the type faces and sharp high points in the edges provide an effective and simple means for preventing local deformation of the ball cover during impression operations because said ridges sink into the cover and provide traction for the die thereon, so that a clear cut impression is made in the ball cover. The grooves also retain ink so that it is not spread over the area surrounding the type impression.

What is claimed is:

In an arcuate die for directly printing a row of marks intaglio in the exterior, impressionable cover of a golf ball the combination of a number 25 of type characters having their bases mounted in a row on the die, each character having a face raised with respect to its base and adapted for impression making engagement with said cover, beard portions extending upwardly from the base 30 to the margins of said face, sharply defined, serrated edges for each type character formed at the intersection of the face and the beard portions and having a continuous series of alternate high 35 and low points, a number of non-intersecting depressions formed across the face of each type character and inclined with respect to the type row, said depressions extending between low points in the opposed edges of the type character face, and a sharp, ball cover deforming ridge formed between adjacent grooves to form corresponding ink retaining grooves in the bottom of the type impression made in said ball cover.
